Bennett, Jr.

Application September 28, 1942, Serial No. 459,892

14 Claims. (Cl. 199—29)

This invention relates to new and useful improvements in duplex rail assembling elevators and in attachments therefor.

One object of the invention is to provide an improved duplex rail assembly mechanism which is adapted for use with any type of elevator wherein the rails are movable longitudinally relative to the line of matrices being assembled, the mechanism being an improvement on our co-pending application, Serial No. 419,432, filed November 17, 1941.

An important object of the invention is to provide an improved duplex rail assembly wherein the upper rail thereof is capable of an elongate longitudinal movement relative to the lower rail, whereby the upper rail may be disposed either in a position overlying and in alignment with the lower rail in which event the matrices will fall onto the upper rail, or said upper rail may be shifted out of longitudinal alignment with the lower rail to offset the end of said upper rail with respect to the end of the lower rail so that the matrices may be deposited directly upon the lower rail, the shifting of the upper rail being accomplished automatically.

A particular object of the invention is to provide an improved duplex rail assembly having means actuated by the insertion of a space band into the device for automatically shifting the upper rail, whereby subsequent matrices fed into the device are deposited upon the lower rail.

A further object of the invention is to provide an assembly, of the character described, wherein the upper rail is maintained in a shifted position after its movement to such position by the insertion of a space band, until said rail is manually returned to its original or starting position, whereby after actuation of the upper rail all subsequent matrices are deposited upon the lower rail until a manual operation is performed to again locate the upper rail in position for receiving additional matrices.

Another object of the invention is to provide an improved duplex rail assembling elevator wherein the automatically operated means which accomplishes the shifting of the upper rail may be locked or latched in a retracted or inactive position, whereby the use of such automatic means is optional with the operator.

Still another object of the invention is to provide an apparatus, of the character described, having the automatic actuating mechanism for its upper rail, which rail is not only slidable longitudinally but is also capable of a lateral or horizontal movement which retracts the entire rail

from its position overlying the lower rail, whereby the automatic feature is combined with the advantages of a slidable and retractile upper rail.

5 A construction designed to carry out the invention will be hereinafter described, together with other features of the invention.

The invention will be more readily understood from a reading of the following specification and 10 by reference to the accompanying drawings wherein an example of the invention is shown and wherein:

Figure 1 is a view in elevation of a duplex rail assembly elevator front having incorporated the 15 improved rail assembly, constructed in accordance with the invention.

Figure 2 is a transverse, vertical sectional view, taken on the line 2—2 of Figure 1,

Figure 3 is an isometric view of the actuating 20 bar,

Figure 4 is an enlarged plan view of the retainer base block of the automatic actuating mechanism,

Figure 5 is a view, partly in section and partly 25 in elevation, of the rear side of the elevator front, the actuator being in a starting position,

Figure 6 is a transverse, vertical sectional view, taken on the line 6—6 of Figure 5,

Figure 7 is a view similar to Figure 5, and showing the actuator in a shifted position,

Figure 8 is a transverse, vertical, sectional view, taken on the line 8—8 of Figure 7, and

Figures 9, 10 and 11 are schematic plan views 30 of the actuating mechanism and illustrating the various positions of the parts during the operation of said mechanism.

In the drawings, the numeral 10 designates the frame of the front portion of an assembling elevator which includes a solid body 11 having an offset depending shank 12. The central portion of the shank is cut out to reduce the weight thereof and the lower portion of said shank has a bolt hole 13 therein, whereby a suitable bolt (not shown) may pass therethrough to secure the frame 10 to the usual Linotype machine (not shown).

The body portion 11 has a substantially flat upper surface 14 and this surface is adapted to support the upper rail assembly. Below the surface 14, the rear surface of the body portion 11 is offset or shouldered near its upper portion to provide a lower rail 15 which extends longitudinally throughout the length of said body. An upper rail 16 is slidable upon the flat surface 14 of the body (Figures 6 and 8) and the rear edge portion

of the upper rail extends beyond the rear wall of the body so as to overlie the lower rail 15. The usual pivotally mounted gate 10a is mounted on the body 11 and normally overhangs the rail assembly, as is clearly shown in Figure 1.

A laterally movable actuating bar or element 17 overlies the upper rail 16 and extends longitudinally above the body portion 11 of the frame, the ends of said bar or element being confined by small blocks 18 (Figure 1). The underside of the actuating bar or element is formed with a longitudinal rib 19 which is adapted to engage a longitudinal groove 20 formed in an extension 16a which is made integral with the upper rail 16 (Figure 6). Manifestly, the rib and groove set up a connection between the extension 16a and the actuating bar or element 17 and when said bar or element is moved laterally or transversely of the body 11 of the frame, a transverse movement is imparted to the extension and to the upper rail 16. This transverse movement of the upper rail is limited in one direction by a longitudinally extending, flanged retaining bar 21 which is secured to the blocks 18, the flange of said retaining bar co-acting with an upstanding longitudinal flange 22 formed on the upper rail. Movement of the rail 16 in an opposite direction is limited by the ends of said rail striking the forward portion of each block 18. The amount of movement which the rail 16 may undergo laterally is sufficient to retract the outer vertical edge of said rail inwardly into the body so that this edge is substantially flush with the rear wall of the body 11 above the lower rail 15. Thus, when the rail 16 is in the position shown in Figures 6 and 8, the upper rail overlies the lower rail but when moved in a direction to the right in these figures, the upper rail will be retracted inwardly out of alignment with the lower rail.

The lateral movement of the upper rail is accomplished through a hand lever 23 which is secured to a shaft 24 mounted in suitable ears or bearings 25 which are formed integral with the body 11. Actuating arms 26 are secured to the shaft 24 and have their upper ends operatively connected with the actuating bar or element 17. Manifestly, when the lever 23 is swung, the shaft 24 is rotated and a lateral or transverse movement is imparted to the bar or element 17 and to the upper rail 16 connected therewith.

It will be obvious that the rail 16 is movable longitudinally on the upper surface 14 of the body 11, such longitudinal movement being permitted because of the rib and groove connection between the rail 16 and the laterally movable actuating bar 17. To permit manual movement of the rail 16 longitudinally on the upper surface of the body, the extension 16a is formed with a thumb piece 27 which may be suitably secured thereto. An angular keeper 28 is secured to the upper surface of the thumb piece and overlies the laterally movable actuating bar or element 17, as is clearly shown in Figure 6. It will be apparent that the thumb piece 27 provides a means whereby a manual sliding movement of the upper rail 16 longitudinally of the body 11 may be accomplished.

In order to resiliently maintain the upper rail 16 in a starting or normal position, with the end of the rail abutting a stop member 29 secured to the body 11, which position is shown in Figure 5, the extension 16a which is formed integral with the upper rail 16 is provided with a depending rod 30. This rod extends downwardly through a longitudinal slot 30a (Figures 5 and 6) which is formed within the body and the lower portion of said rod projects into a longitudinal recess 31

which is provided in the rear face of the body 11. A bell crank lever 32 is pivotally mounted on the shank 12 of the frame 10 and has its upper end projecting in a plane in horizontal alinement with the recess 31 and this upper end is formed with an inwardly extending pin 33 which is adapted to engage the depending rod 30. The other arm 34 of the lever which is located at the lower end thereof has one end of a coiled spring 35 connected thereto, the other end of said spring being secured to the shank of the frame. The spring 35 constantly exerts its tension to force the pin 33 at the upper end of the lever 32 into engagement with the depending rod 30 and thus, the spring tension constantly urges the upper rail 16 to its original or starting position in engagement with the stop 29.

A spring-pressed ball 36 is mounted within the body 11 and is located in spaced relation to the stop 29. The upper end of the ball 36 projects upwardly above the surface 14 of the body 11 and the rail 16 is arranged to ride over the ball. When the upper rail 16 is slid longitudinally from its original or starting position, as shown in Figure 5, to the position shown in Figure 7, the end of said rail has moved beyond the spring-pressed ball 36, with the result that the surface of the ball projects into the path of the rail. Therefore, in order to return the rail to its original or starting position adjacent the stop 29, it is necessary that sufficient force be exerted on the rail to overcome the friction of the spring behind the ball 36. The spring 35, which is acting on the bell crank lever 32 and which is the force tending to return the rail 16 to an original or starting position, is not sufficient to overcome the frictional resistance of the spring-pressed ball 36 and therefore, after the rail 16 has been moved from its original or starting position beyond the ball 36, it is necessary that a manual force be applied to the rail in order to return it to its original position.

It might be noted that an upper rail which is capable of a longitudinal sliding movement and which is also capable of being retracted laterally has been disclosed in our copending application and the present construction of this upper rail is an improvement on the device disclosed in such application.

The matrices (not shown) which are fed into the elevator will strike the upper rail 16 when said rail is in the position shown in Figure 5, since said matrices are fed into the device at the end adjacent the stop member 29. If desired, several matrices may be deposited upon the upper rail and then the rail moved manually by means of the thumb piece 27, in which event the matrices would fall downwardly onto the lower rail 15. As explained, the upper rail 16 may be held in substantially the position shown in Figure 7 by means of the spring-pressed ball 36, whereby the subsequent matrices are deposited directly upon the lower rail 15. There are many types of lino-type make-up work, such as telephone directories, in which it is desirable that the upper rail 16 be moved from its original or starting position at a pre-determined time. For example, in printing such material as telephone directories, it is the practice to make the first portion of the line in bold-faced type, the middle portion in light-faced type and the end portion in bold-faced. It would thus be desirable to feed the matrices forming the first portion onto the upper rail, then shift the rail to permit the intermediate matrices to be deposited directly upon the lower

rail and finally return the upper rail to its original position to permit the deposit of the remaining matrices upon the upper rail.

For automatically shifting the upper rail from its original or starting position, which will be hereinafter referred to as a closed position, an actuating mechanism is mounted within the recess 31 and is located at that end of said recess which is adjacent the point of entry of the matrices. This actuating mechanism includes a block 40 which is substantially rectangular in shape and which is provided with a recess 41 in one side thereof (Figure 4). The recess has a general rectangular shape and a transverse slot 42 extends from the recess and opens upon the opposite side of said block. A flat spring 43 having one end secured to the side of the block by a screw 44 overlies and closes the open side of the recess 41 and this spring has a wedge-shaped lug 45, which extends inwardly into said recess, mounted thereon. An arcuate leaf spring 46 has one end secured to the opposite side of the block 40, while its other end is curved inwardly through the slot 42, the end of said spring extending into the recess 41. An upstanding partition or wall 47 extends upwardly from the bottom of the recess 41 and is disposed centrally and longitudinally of said recess, the ends of the partition terminating in spaced relation to the vertical end walls of the recess 41. An upstanding guide pin 48 is provided at one corner of the block 40 and is arranged to co-act in guiding the movement of an actuating bar 50.

The actuating bar 50 is clearly shown in Figures 3 and 9 to 11 and includes a flared body 51 which is arranged to overlie and rest upon the upper surface of the block 40. The body 51 of the actuating bar is formed with an outwardly extending lug 52 having its upper surface beveled as shown at 53. The opposite end of the body 51 is formed with an elongate groove 54 in its under side and when the bar is in position on the block, the groove 54 receives the upstanding pin 48 which, as explained, is located at one corner of said block. A depending pin 55 extends downwardly from the under side of the bar and is disposed adjacent one end of the groove 54, this pin being arranged to project downwardly into the recess 41 of the block. An extension 56 having an inclined edge 56a (Figures 9 to 11) is formed integral with the body 51 at the end opposite the beveled lug 52 and this extension is arranged to engage over the depending rod 30 which is formed on the upper rail 16 and which is located within the recess 31 of the body 11 of the frame.

Normally, the actuating bar is in the position shown in Figure 9, with the depending pin 55 of said bar in the position shown in full lines in Figure 4, such position being indicated at A. The bar is held in this position by the engagement of the rod 30 with the end of said bar, the rod being forced against the bar because of the bell crank lever 32 which is under the influence of the spring 35. In this position, the beveled lug 52 on the bar 50 is projecting outwardly beyond the recess 31 and also beyond the side wall of the block 40, whereby this lug is in a vertical plane beyond the upper and lower rails 15 and 16, as is clearly shown in Figure 6. When a space band is fed into the device, this band will engage the end of the lug 52 and due to the bevel thereof will urge the actuating bar 50 in a direction to the right in Figures 5 and 9.

As the bar 50 is moved to the right, it will transmit a similar motion to the upper rail 16 because the end of said bar is in engagement with the rod 30 of said upper rail. Thus, the upper rail 16 will be slid longitudinally away from the stop 29 and the end of the rail is spaced from said stop. Thus, subsequent matrices fed into the device will fall downwardly onto the lower rail 15. Because of the spring 10 pressed ball 36 exerting a greater frictional resistance than the coil spring 35, the upper rail 16 will remain in this position until manually returned to its original or starting position against the stop 29.

It may be desirable to render the actuating mechanism which includes the actuating bar 50 inactive at certain times and in order to effect a retraction of the bar so as to retract the lug 52 thereof into the recess 31, the bar 50 is provided with an angular hook 57 which has a lateral leg 57a and which is preferably formed integral with the vertical edge of the bar 50 opposite the edge on which the lug 52 is located. The hook 57 extends through a horizontal slot 58 (Figure 2) which is formed in the body 11 of the frame and the lateral leg 57a extends parallel to the front wall of the body portion 11. The leg 57a is engageable over a cam link 59, which link has its upper end reduced whereby an inclined cam surface 59a is formed nearer the upper end of said link. The lower end of the link is pivotally connected to a rotatable sleeve 60 which surrounds the shaft 24 and a suitable handle 61 is secured to the sleeve. Manifestly, when the sleeve 60 and link 59 are in the position shown in Figure 2, the enlarged lower end of the link is disposed between the lateral leg 57a of the hook and the front wall of the body 11, whereby the bar 50 is moved inwardly of the body and the lug 52 of said bar is retracted within the recess 31 of the body. When the sleeve 60 is rotated in a counter-clockwise direction in Figure 2, the cam link 59 is lowered, whereby the reduced upper end of the cam link is disposed between the lateral leg 57a and the wall of the body 11 and in this position, the bar 50 may move outwardly so that its lug 52 is projecting outwardly as shown in Figure 6. Thus, by manipulating the sleeve 60 and the cam link 59, the lug 52 of the actuating bar 50 may be projected outwardly into an operative position or may be retracted inwardly so as to render the actuating mechanism inactive.

In the operation of the device, the parts are in the position shown in Figure 5, with the upper rail 16 in its extended position overlying the lower rail and also in an original or starting position adjacent the stop 29. The actuating bar 50 of the actuating mechanism is in the position shown in Figure 9, with the guide pin 55 on the lower end of the bar 50 in the position shown in full lines and indicated by the letter A in Figure 4. The cam link 59 is of course in a lowered position at this time and the lug 52 of the actuating bar 50 is projecting beyond the front wall of the body 11.

As matrices are fed into the assembly elevator, said matrices will be deposited upon the upper rail 16 because said rail is in its projecting position overlying the lower rail. The lug 52 on the actuating bar is in a plane sufficiently below the lower rail 15 so that any matrices deposited either upon the upper or lower rail will not engage said lug. Therefore, the matrices may be fed into the assembly and will be retained by the upper rail

so long as the parts remain in the position shown in Figure 5.

The first space band which is fed into the elevator and which is of an increased length as compared to the matrices will engage the lug 52, resting upon the beveled upper surface 53 thereof. As the space band is moved farther into the elevator, that is, as said band moves to the right along the rails in Figure 5, the engagement of said band with the inclined surface of the lug 52 will impart a shifting or sliding movement to the actuating bar 50, such movement being permitted by the guide pin 55 of said bar moving longitudinally of the recess 41 in the block 40, said pin moving toward the wedge-shaped lug 45 within the recess.

As movement is imparted to the actuating bar by the inserted space band, the bar 50 through its engagement with the depending rod 30 of the upper rail 16 will impart a similar sliding movement to the upper rail, whereby the end of the rail will be moved away from the stop 29. Thus, the upper rail is slid longitudinally and since its end is spaced from the stop, the subsequent matrices which are fed into the elevator will drop directly upon the lower rail 15. Movement of the actuating bar longitudinally of the frame and of the block 40 will continue until the pin 55 of said bar strikes the wedge-shaped lug 45 and by this time, the upper rail 16 has moved beyond the spring-pressed ball 36, which ball will prevent the return of the rail to its original position until an additional manual force has been applied to said rail, as previously explained.

As the pin 55 of the actuating bar 50 engages the lug 45, the spring 43 which carries this lug will be flexed outwardly to permit the pin to pass the end of the upstanding partition 47 (Figure 4) within the recess 41 of the block and as soon as said pin moves past the partition, the spring 43 tends to snap the pin 55 into the position shown in dotted lines in Figure 4, which position is marked B. The bar 50 being pivotally connected to the block 40 through the pin 48 and groove 54, this movement of the pin 55 will cause a swinging movement to be imparted to the bar, such movement being laterally of the block and this position of the parts is shown in Figure 10. When the bar 50 is swung in this manner, the lug 52 is swung inwardly of the block and is moved to a retracted position, whereby it is disposed out of the path of the space band. The actuating bar 50 is thus rendered inactive and the parts will remain in this position until a manual return of the upper rail is effected.

When the upper rail 16 is manually returned to its original or starting position, the rod 30 of said rail will engage the end of the actuating bar and will slide said bar to the position shown in Figure 11, the pin 55 being moved to the dotted line position C in Figure 4. As this sliding movement is imparted to the actuating bar through the rod 30, the pin 55 will engage the curved spring 46, which spring must flex to permit the pin to pass the end of the partition 47. Thus, the spring 46 is distorted outwardly to permit by-passing of the pin 55 and as soon as said pin clears the end of the partition, the pin 55 is snapped into its original position on the opposite side of the partition 47, as shown in full lines A in Figure 4. Thus, a snap action is effected in returning the bar to its original position, whereby its lug 52 is again disposed outwardly in a position adapted to be

engaged by the next space band inserted into the assembly.

From the foregoing, it will be seen that a simple and efficient assembly elevator is provided. The matrices are fed into the machine and so long as the upper rail is in the position shown in Figures 5 and 6, said matrices will be deposited upon said upper rail. Upon the insertion of the first space band into the device, the actuating mechanism is set into operation, whereby the upper rail is shifted to an open position so that the subsequent matrices will be deposited upon the lower rail. When it is desired to again deposit matrices upon the upper rail, a manual shifting of the upper rail will result in disengaging the actuating bar 50 from the space band and returning the same to its original position ready for the next operation. The actuating mechanism may be rendered inactive at any desired time by merely manipulating the sleeve 60 and raising the cam link 59. Of course, if it is desired to retract the entire upper rail 16 it is only necessary to swing the lever 23 and retract the rail through the element 17 which is moved laterally of the body 11 by the operation of the lever 23.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. A duplex rail assembling elevator including, a frame, a lower rail carried by said frame, an upper rail mounted on the frame and disposed above the lower rail, said upper rail being movable longitudinally of said frame, and means supported on said frame and engageable by a space band which is fed into the elevator for imparting a longitudinal movement to said upper rail.

2. A duplex rail assembling elevator including, a frame, a lower rail carried by said frame, an upper rail mounted on the frame and disposed above the lower rail, said upper rail being movable longitudinally of said frame, and movable actuating means supported on said frame and operatively connected to the upper rail for imparting a longitudinal movement to said upper rail, said actuating means being normally disposed in the path of a space band which is inserted into the elevator so as to be engaged and operated by said space band, whereby the upper rail is automatically moved when said space band is inserted into the elevator.

3. A duplex rail assembling elevator as set forth in claim 2, with means for retracting the actuating means out of the path of the inserted space band to render said means inactive.

4. A duplex rail assembling elevator including, a frame, a lower rail formed on said frame, an upper rail mounted on the frame and movable longitudinally thereof, movable means projecting beyond said rails adapted to be engaged by a space band which is fed into the elevator, and means operatively connecting said projecting means to the upper rail, whereby as the projecting means is moved by the space band the upper rail will be moved longitudinally of the frame.

5. A duplex rail assembling elevator including, a frame, a lower rail formed on said frame, an upper rail secured to the frame and movable

longitudinally thereof, movable means projecting beyond said rails adapted to be engaged by a space band which is fed into the elevator, means operatively connecting said projecting means to the upper rail, whereby as the projecting means is moved by the space band the upper rail will be moved longitudinally of the frame, and means for moving the projecting means out of engagement with the space-band after a pre-determined travel thereof.

6. A duplex rail assembling elevator including, a frame, a lower rail formed on said frame, an upper rail secured to the frame and movable longitudinally thereof, an actuating element operatively connected to the upper rail, a projection formed on said element adapted to be engaged by a space band whereby movement of the space band will move the element and the upper rail longitudinally of the frame, and means for automatically retracting the projection and element from engagement with the space band after a pre-determined longitudinal movement of the element.

7. A duplex rail assembling elevator as set forth in claim 5 and means for manually retracting the projecting means out of the path of an inserted space band to render the same inactive.

8. A duplex rail assembling elevator as set forth in claim 2, with means for automatically disengaging the actuating means from the space band after said band and means have traveled a pre-determined distance.

9. A duplex rail assembling elevator including, a frame, a lower rail carried by said frame, an upper rail mounted on the frame and disposed above the lower rail, said upper rail being movable longitudinally of said frame, movable actuating means supported on said frame and operatively connected to the upper rail for imparting a longitudinal movement to said upper rail, said actuating means being normally disposed in the path of a space band which is inserted into the elevator so as to be engaged and operated by said space band, whereby the upper rail is automatically moved when said space band is inserted into the elevator, means for automatically disengaging the actuating means from the space band after said band and means have traveled a pre-determined distance, and means associated with the upper rail for preventing its automatic return to its original starting position after it has been moved by said actuating means.

10. A duplex rail assembly elevator as set forth

in claim 9, with manually operated means for returning the upper rail and actuating means to their original starting positions.

11. As a sub-combination in a duplex rail assembling elevator having a longitudinally movable upper rail of an actuating mechanism for imparting movement to said rail, said mechanism including, a support adapted to be mounted on the elevator, an actuating bar slideable longitudinally and capable of a swinging movement upon the upper surface of said support, said bar being adapted to be operatively connected with the upper rail, and a projection on said bar normally disposed in the path of a space band which is fed into the elevator, whereby said projection is engaged by the band and movement of said band imparts movement to the bar and upper rail.
12. The sub-combination as set forth in claim 11, together with co-acting means carried by the support and by the actuating bar for automatically swinging the bar to disengage its projection from the space after said band and bar have been moved a predetermined distance.
13. The sub-combination as set forth in claim 11, together with a manually operated means for swinging the bar to retract and hold the projection out of the path of the space band to render the mechanism inactive.
14. As a sub-combination in a duplex rail assembling elevator having a longitudinally movable upper rail of an actuating mechanism for imparting movement to said rail, said mechanism including, a support adapted to be mounted on the elevator, an actuating bar slideable longitudinally and capable of a swinging movement upon the upper surface of said support, said bar being adapted to be operatively connected with the upper rail, a projection on said bar normally disposed in the path of a space band which is fed into the elevator, whereby said projection is engaged by the band and movement of said band imparts movement to the bar and upper rail, co-acting means carried by the support and actuating bar for automatically swinging the bar to disengage the projection from the space band after said band and bar have been moved a predetermined distance, and a manually operated means for swinging the bar to retract and hold the bar out of the path of the space band to render the mechanism inactive.

HORACE C. WAUSON.
